UNITED STATES PATENT OFFICE

LEWIS J. BAZZONI, OF SWAMPSOFT, MASSACHUSETTS, ASSIGNOR TO UNITED SHOE MACHINERY CORPORATION, OF PATERSON, NEW JERSEY, A CORPORATION OF NEW JERSEY

HEEL COVERING MACHINE

Application filed November 2, 1927. Serial No. 230,536.

This invention relates to machines for operating upon shoe heels, particularly grooved heels, and is herein illustrated as embodied in a machine for facilitating the covering of heels with sheet material.

One important object of the invention is to provide an efficient machine for accurately and rapidly securing to a heel block the meeting edge portions of a piece of heel covering material, an operation which has heretofore been performed by hand. A more specific object is to provide a machine for tucking into the groove of a grooved heel block the meeting edge portions of the covering material.

With these objects in view, the invention comprises a machine in which are combined means for positioning a heel block and means for securing in succession to the block the meeting edge portions of the heel cover.

In the illustrated embodiment of the invention, the machine is provided with a single means arranged to secure the cover to a heel block, as by tucking the covering material into a groove in the block, the preferred form of means for accomplishing this function consisting of a reciprocable tucking blade which is movable into and out of the groove in the block, and is operative upon the two meeting edge portions of the heel cover in succession.

In this connection, invention is also to be recognized in the combination with a tucking blade which is very thin, and, therefore, liable to be deformed if subjected to much bending force, of means for positioning a grooved heel block with its groove in the plane of said blade and means for effecting relative movement of the block and the blade in the plane of the blade, to tuck heel covering material into the groove. By mechanically restricting the tucking movement to the plane of the blade the application of bending force to the blade is avoided and it is possible to employ an extremely thin blade, much thinner than would otherwise be practicable. This is very advantageous with some kinds of heel covering material, inasmuch as it permits tucking the material into the groove without compressing the material beyond the

limit of its elastic recovery and when the tucking blade is withdrawn the said material can expand to fill the groove, so that a very secure and neat attachment is obtained.

A further feature of the invention consists in the provision, in a machine for operating upon a grooved heel block, of means co-operating with a narrow, approximately parallel walled groove in the block for positioning the block for an operation thereon, said means comprising a blade which operates to tuck heel covering material into the groove.

Other features and advantages of the invention will become apparent from reading the following detailed description of one embodiment thereof in connection with the accompanying drawings, in which

Fig. 1 is a view, in side elevation, of a heel cover tucking machine embodying the invention;

Fig. 2 is a view of the head of the machine in front elevation;

Fig. 3 is a perspective view showing details of mechanism for effecting angular adjustment of the tucking blade;

Figs. 4, 5, 6 and 7 illustrate the successive steps in the operation of tucking the edges of the covering material into the groove in a heel block; and

Fig. 8 is a perspective view of the covered heel.

In the drawings 10 indicates a base which is designed to be supported upon a bench and upon which is mounted a fixed heel block positioning member in the form of a clamping jaw 12 adapted to engage the attaching face of a heel 14 to be operated upon.

A co-operating, movable, clamping jaw 16 is mounted upon an arm 17 for pivotal movement about a horizontal, stationary shaft 18 which is secured in brackets 20 upon the base 10. Also mounted for pivotal movement about the shaft 18 is a lever 22, the front end of which is connected by a rod 24 to a treadle 26 and the rear end of which is provided with a seat for a short, stiff, compressed spring 28. The upper end of the spring 28 bears against an arm 30 integral with, and projecting rearwardly from, the movable clamping jaw carrying arm 17. Co-operating,

abutting surfaces 32 and 34, upon the arm 17 and the lever 22, respectively, are normally held in engagement with each other by the expansive force of the spring 28. From the foregoing it will be apparent that when the treadle 26 is depressed the movable clamping jaw 16 will be moved toward the fixed jaw 12, to clamp and support in position for operating upon it a heel block to which a cover is to be applied. The spring 28 constitutes a yielding connection between the treadle 26 and the clamping jaw 16 moved thereby, making it easy for the operator to apply about the same amount of clamping force to each heel block without careful attention to, or control of, the force applied to the treadle by his foot.

The cover to be applied to the heel may consist of a piece of more or less yielding sheet material 36. Thin leather is very often used for this purpose, although many other materials are also extensively used, and the use of such other materials as are suitable is included within the capabilities of the machine. When using the illustrated machine, the covering material 36 is secured to the heel block 14 by tucking the meeting edge portions of the cover into a narrow, approximately parallel walled groove 38 formed in the breast face of the heel block. Preferably the normal thickness of the heel covering material is equal to at least half the width of the groove 38, so that the two edge portions of the material, when tucked into the groove, will substantially fill the groove. An adhesive may be used or not, as the condition of the work may require, to aid in securing the edge portions of the heel covering in the groove.

To co-operate with the groove to position the heel block for operation thereon and to tuck the covering material into the groove in the block, the machine is provided with a very thin vertical blade 40 which is carried by an oscillatory arm 42 pivoted upon a stationary horizontal shaft 44 mounted in brackets 46 arising from the machine base 10. Extending rearwardly from the arm 42 is an arm 48 to which is attached a pull spring 50 tending, at all times, to elevate the tucking blade 40. A downward extension 52, rigid with the arm 42, is engaged by a roll 54 on the upper end of a bell crank lever 56, the lower end 58 of which is connected by a rod 60 to a treadle 62.

It will be readily understood that depression of the treadle 62 by the operator will cause the lever 56 to move the extension 52 backward, lowering the tucking blade 40 into the position shown in Fig. 1, against the tension of the spring 50.

In order to accommodate variations in the direction and location of the groove 38 in the heel block, provision is made for angular adjustment of the blade transversely of the

direction of its movement and also for movement of the blade mounting longitudinally of the blade. To these ends the blade 40 is secured in a rigid blade holder 64 which is movable in a transverse plane about a pivot bolt 66 which is carried by a mounting 68 movable longitudinally of the blade upon the arm 42 and adapted to be secured thereto by a clamping nut 70. The forward end of the mounting 68 is extended at both sides, forming a segmental head 72 which is provided with a series of index holes 74 through any one of which may be inserted a pin 76 which enters and fits a hole in the blade holder 64. When the pin 76 is withdrawn the tucking blade may be moved angularly to any desired position, where it may then be secured by inserting the pin through the appropriate hole in the index head 72.

Regardless of the position to which the blade 40 is adjusted, its operative movement is in its own plane and no bending force is applied to it. This makes it practicable to employ a tucking blade only a few thousandths of an inch thick, which would be impracticable with a hand tool because such a thin blade is so easily bent that it would be impossible to avoid bending or breaking it in ordinary use.

The mode of operation of the machine is as follows: A grooved heel block is selected and a heel cover, which may be coated with cement, is applied to the rear and side faces of the block, the end portions of the cover extending beyond the breast corners of the block. The tucking blade 40 having been adjusted both as to location and direction to suit the work at hand, the treadle 62 is depressed until the blade is in the position shown in Fig. 1. The attaching face of the heel block is then placed against the fixed clamping jaw 12 with the block in such a position that the tucking blade is in the groove in the block. The treadle 26 is now depressed and the movable clamping jaw 16 is caused to engage the tread face of the heel block, which is thus clamped and held firmly in the position shown.

While the clamp operating treadle 26 is kept depressed, the treadle 62 is released, permitting the spring 50 to raise the tucking blade to a position removed from the heel, leaving the breast face of the latter unobstructed. One of the projecting end portions of the cover is next laid down upon the breast face of the heel block with its edge portion across the groove 38, as shown by the broken lines at 78 in Fig. 4. The treadle 62 is then depressed and the tucking blade 40 tucks the edge portion of the heel cover into the groove 38 in the block, as shown in full lines in Fig. 4.

The tucking blade is now retracted and the second edge portion of the cover is lapped across the groove 38. The treadle 62 is again

depressed, causing the blade to tuck the second edge portion of the cover into the groove, as shown in Figs. 5 and 6. The treadle 62 is released and the blade 40 retracted, as shown in Fig. 7, leaving the cover secured to the heel. The treadle 26 is now released, leaving the covered heel free to be removed from the machine.

As hereinbefore stated, the blade 40 is very thin and the elasticity and thickness of the covering material 36 and the width of the groove 38 may be such that the thin tucking blade will not compress the tucked in edges beyond the limit of their elastic recovery, so that when the blade is withdrawn the covering material will expand and fill the groove completely, as shown in Fig. 7.

Having described the invention, what is claimed as new and desired to be secured by Letters Patent is:

1. In a machine of the class described, the combination of a heel block support, and means for applying in succession to a heel block supported thereby the two meeting edge portions of a sheet of heel covering material.

2. In a machine of the class described, the combination of means for holding a heel block, and means for tucking heel covering material into a groove in the block.

3. In a machine of the class described, the combination of means for supporting a heel block, a tucking device, and means for effecting relative movement of the heel block and the tucking device to tuck heel covering material into a groove in the block.

4. In a machine of the class described, the combination of means for holding a heel block, and a tucking blade movable into a groove in a block supported by the holding means.

5. In a machine of the class described, the combination of a tucking blade which is so thin as to be easily bent, means for positioning a grooved heel block with its groove in the plane of the tucking blade, and means for effecting relative movement of the block and the blade in the plane of the blade.

6. In a machine of the class described, the combination of a tucking blade which is so thin as to be easily bent, means for holding a grooved heel block with its groove in the plane of the tucking blade, and means for reciprocating the blade in its own plane into and out of the groove in the block.

7. In a machine of the class described, the combination of a treadle operated clamp for holding a heel block, and treadle operated means for tucking heel covering material into a groove in a block held in said clamp.

8. In a machine of the class described, the combination of clamp jaws arranged to engage the attaching face and the tread face of a heel block, and a reciprocable heel cover

tucking blade movable into a groove in a block held between said clamp jaws.

9. In a machine of the class described, the combination of a clamp arranged to hold a heel block, and a tucking blade movable into and out of a groove in a block held in the clamp, said blade being angularly adjustable transversely of the direction of its movement.

10. In a machine of the class described, the combination of a clamp arranged to hold a heel block, a tucking blade movable into and out of a groove in a block held in the clamp, a pivotal mounting about which said blade is angularly adjustable, and means for moving said mounting longitudinally of the blade.

11. In a machine for operating upon a grooved heel block, a blade constructed and arranged to enter a groove in the block to position the block for an operation thereon, and mechanism for producing relative movement between the blade and the block to cause the blade to tuck heel covering material into the groove.

12. In a machine of the class described, the combination of means for positioning a heel block, and means for tucking heel covering material into a groove in the block.

In testimony whereof I have signed my name to this specification.

LEWIS J. BAZZONI.
